CLAIM

I claim the ornamental design for a brush with cap, as shown and described.

DESCRIPTION

FIG. 1 is a perspective view of a brush with cap, showing my new design;

FIG. 2 is a perspective view of the brush component shown with the cap removed;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is a front elevational view of the brush with cap shown with the cap affixed on the brush;

FIG. 10 is a rear elevational view thereof;

FIG. 11 is a left side elevational view thereof;

FIG. 12 is right side elevational view thereof;

FIG. 13 is an enlarged top plan view thereof;

FIG. 14 is an enlarged bottom plan view thereof;

FIG. 15 is a front elevational view of the cap component, shown separately for clarity;

FIG. 16 is a rear elevational view thereof;

(Continued)

FIG. 17 is a left side elevational view thereof;
 FIG. 18 is a right side elevational view thereof;
 FIG. 19 is a top plan view thereof; and,
 FIG. 20 is a bottom plan view thereof.
